BATTERY GRID CASTING MACHINE

Albert H. Luhrman, Cincinnati, Ohio

Application August 10, 1936, Serial No. 95,171

3 Claims. (Cl. 22—57)

My invention relates to an improved grid casting machine of the multiple type wherein a plurality of grids are automatically cast, ejected and conveyed out of the machine.

5 The object of my invention is to provide improved grid forming molds, improved means for opening and closing the molds, improved means for accurately delivering predetermined quantities of molten metal to the molds, improved means 10 for ejecting the cast grids and conveying the grids out of the machine.

A further object is to provide a plurality of molds on each side of the lead pot and alternately casting grids on each side of the machine and 15 delivering said grids from the machine.

My invention will be further readily understood from the following description and claims, and from the drawings, in which latter:

Fig. 1 is a plan view of my improved machine. 20 Fig. 2 is a side view of the same, partly broken away.

Fig. 3 is a vertical section of the same, taken in the plane of the line 3—3 of Fig. 1.

Fig. 4 is a detail section, taken in the plane of 25 the line 4—4 of Fig. 2, showing the molds in open position, and

Fig. 5 is a detailed section of the lead pumps, taken in the plane of the line 5—5 of Fig. 1.

My improved machine comprises a frame 11 30 constructed of suitable channels and angle irons arranged to support a central lead pot 12, which has suitable means in conjunction therewith for maintaining the lead or casting material in a molten state. On each side of the lead pot are 35 a pair of channel irons 13 and 14, having suitable openings 15 and 16 therein. A cross shaft 20 extends across the machine and is suitably supported in bearings 21 and has segment gears 22 mounted thereon and arranged to mesh with pinion gears 23, mounted on shafts 24. An eccentric 40 25 is also secured to the shaft 24 and has a connecting rod 26 pivoted to a support 27 as at 28, which support is connected to a cross-bar 29 arranged to reciprocate in the openings 15.

45 On either side of the channels 13 and 14 are rods 30, supported in bearings 31 and having threaded connection with the cross-bar 29.

It will be noted that the segment gears 22 are 50 positioned at right angles to each other to permit alternate movement to the respective bars 29 on each side of the machine. A suitable plurality of lead molds 32 are arranged between the supports 13 and 14 on each side of the machine and comprise stationary parts 33 fixed to cross-bars 55 34, which are suitably secured to the frames 13

and 14, while the complementary movable molds 35 are secured to cross-bars 36 being guided and slidably in the openings 16. The rods 30 extend through these cross-bars and have collars 37 arranged to contact the cross-bars for moving the 5 movable molds endwise away from the stationary molds against the tension of springs 38 confined by collars 39.

Above each of the molds is provided a lead cup 40, pivoted on supports 41 and interconnected as 10 by a bar 42 having a linkage connection 43 with a cam 44 mounted on the shaft 20. Suitable lead pumps 50 extend into the lead pot 12. A central shaft 51 is supported above the lead pot and has rocker arms 52 thereon for alternately pumping 15 lead through the pumps 50, through tubes 53 into the lead cups 40. Adjustments are provided for regulating the length of the stroke of the lead pump for pumping the exact quantity of lead to the lead cup necessary to form a complete grid. 20

The shaft 51 has a rocker arm 54 secured to one end thereof and said rocker arm has cables 55 connected to the respective slides 29 for rocking the shaft 51 on the forward movement of the respective slides 29 for operating the pumps. 25

The shaft 20 is suitably driven by a chain 60 received over sprocket wheel 61 on the shaft 20 and about a sprocket wheel 62, extending from a speed change mechanism 63 which is driven by an electric motor. 30

Suitable conveyors 65 are supported below the molds on each side of the machine and are driven by sprocket chains 66 from the speed change mechanism. Slides 67 are arranged below the molds for guiding cast grids to the conveyor. 35

Suitable knock-out pins 70 are provided in the stationary mold, being connected to cross-bars 71, which bars are supported on studs 72 having springs 73 interposed between the bar and the mold support. The movable cross-bars 36 are 40 provided with studs 74 arranged to contact a knock-out bar 71 when the molds are open for causing the pin 70 to free the grid from the mold 33.

In the operation of my improved casting machine, the lead is alternately pumped to the respective lead cups on each side of the machine and as the molds close, the lead cups 40 are tipped for pouring the lead into the molds and the molds remain in this position until the complementary 45 gear segment causes rotation of the pinion gear 23 which rotation causes eccentric 25 to rotate, thus opening the molds. As the molds are open 50 the casting is ejected, slides down the slide 67 to the conveyor 65 and is carried out of the ma- 55

chine. As this operation takes place on one side of the machine, a similar operation through like parts is alternately enacted on the other side of the machine. Thus it will be seen that while grids are being cast on one side of the machine, they are being ejected on the other side of the machine.

While I have described the elements composing one set of molds and their actuating parts, it will be apparent that all of the molds are similar in construction on both sides of the machine and are actuated in like manner.

Having thus fully described my invention, what I claim as new and desire to secure by Letters Patent, is:

1. In a casting machine, the combination of a lead pot, a plurality of pairs of complementary molds on each side of said lead pot, one part of each mold being stationary, the other part of each 20 mold being mounted on a slide, a cross-shaft below said slides, a pair of segment gears alternately spaced on said shaft, shafts above said first-named shaft, pinion gears on said shafts arranged to be rotated by the respective segments, and crank arms on said second-named shafts having connection with said slides for opening and closing said molds.

2. In a casting machine, the combination of a lead pot, a plurality of pairs of complementary 30 molds on each side of said lead pot, one part of

each mold being stationary, the other part of each mold being mounted on a slide, a cross-shaft below said slides, a pair of segment gears alternately spaced on said shaft, shafts above said first-named shaft, pinion gears on said shafts arranged to be rotated by the respective segments, 5 crank arms on said second-named shafts having connection with said slides for opening and closing said molds, and a lead cup pivoted above each of said molds and means for tipping said cups 10 upon closing of said molds.

3. In a casting machine, the combination of a lead pot, a plurality of pairs of complementary molds on each side of said lead pot, one part of each mold being stationary, the other part of each 15 mold being mounted on a slide, a cross-shaft below said slides, a pair of segment gears alternately spaced on said shaft, shafts above said first-named shaft, pinion gears on said shafts arranged to be rotated by the respective segments, 20 crank arms on said second-named shafts having connection with said slides for opening and closing said molds on the respective sides of said lead pot alternately, a lead cup pivoted above each of said molds, means for tipping said cups 25 upon closing of said molds, means for releasing the castings upon opening of said molds, and conveyors for carrying said released castings out of said machine.

ALBERT H. LUHRMAN. 30
